UNITED STATES PATENT OFFICE.

FRANCIS L. GORDON, OF BUFFALO, NEW YORK.

TOY PISTOL.

SPECIFICATION forming part of Letters Patent No. 404,275, dated May 28, 1889.

Application filed June 5, 1888. Serial No. 276,071. (No model.)

To all whom it may concern:

Be it known that I, FRANCIS L. GORDON, a citizen of the United States, residing at Buffalo, in the county of Erie and State of New York, have invented certain new and useful Improvements in Toy Pistols; and I do hereby declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 My invention consists in a certain improved construction in toy pistols for firing percussion-caps and throwing fire-crackers into the air, all of which will be fully hereinafter described and claimed.

20 In the drawings, Figure 1 is a side view of the pistol, with one half of the shell removed and showing the parts adjusted for firing. Fig. 2 is a similar view showing the position of parts after the pistol has been fired, and 25 Figs. 3 and 4 are detached detail views.

Referring to the drawings, the frame of the pistol is cast of metal, in two pieces or half-shells, *a*, one of which is shown in the drawings in Figs. 1 and 2. The half-shells *a* are 30 recessed to receive the operative parts and riveted together to form the complete shell.

a' is the front or barrel portion adapted for the reception of the fire-cracker, as seen in Fig. 1.

35 *b* is a rod or plunger, its front end having the enlarged head *b'*, loosely fitting the bore of the barrel *a'*. Its rear end is enlarged and has the side lug, *b*², which slides in a slot in the frame and on the under side the shoulder or catch *b*³. A spiral spring, *b*⁴, is interposed between the head *b'* of the plunger *b* and the annular shoulder *a*² in the barrel *a'*.

40 *b*⁴ (see Fig. 3) is a thumb-piece for manipulating the plunger, which extends outwardly 45 and rides in a slot in the side of the frame.

c is a catch pivoted in the frame, having the arm or extension *c'*, against the under side of which rests the bent spring *c*². When the plunger *b* is pulled back, its catch *b*³ engages with the pivoted catch *c*, and is held in 50 such engagement by the spring *c*², which ex-

erts an upward pressure against the arm *c'* of the catch *c*, as clearly shown in Fig. 1.

d is the hammer, pivoted at *d'* in the frame and having the enlarged outer end, *d*², adapted 55 to strike in the recess or seat *a*³, in which the percussion-cap is placed to be exploded by the blow of the hammer.

*d*³ is an arm extending out rearwardly from the hammer *d*, against the under side of which 60 one end of the spring *d*⁴ presses.

*d*⁵ is a shoulder or catch on the hammer near the pivot-point.

e is the trigger, pivoted in the frame at *e'*.

*e*² is an arm or forward extension adapted 65 to engage with the arm *c'* of the catch *c*.

*e*³ is a shoulder or catch for engagement with the catch *d*⁵ of the hammer *d*, and *e*⁴ is a rearwardly-extending arm, against which the under side of the spring *d*⁴ presses. 70

The different parts just described are set for action, as shown in Fig. 1, the spring *d*⁴ holding the arm *e*² of the trigger down against the frame, the catch *e*³ of the trigger engaging the catch *d*⁵ of the hammer, and the arm *e*² 75 of the trigger resting over the arm *c'* of the catch *c*. When the trigger *e* is pulled back, its arm *e*² throws down the arm *c'* of the catch *c*, which is thus disengaged from the catch *b*³ of the plunger *b*. The spiral spring *b*⁴ throws 80 forward the plunger and forcibly ejects the fire-cracker just as it is about to explode. In the meantime the shoulders *e*³ and *d*⁵ of the trigger and hammer are disengaged, allowing the hammer *d* to be thrown by the action of 85 spring *d*⁴ against the percussion-cap in the recess or seat *a*³.

It is apparent that the throwing of the fire-cracker and the explosion of the cap can be done separately or simultaneously at pleasure. 90

Another feature is provided at the butt-end of the pistol for exploding caps, consisting of the holder *f*, pivoted by means of its lugs *f'* in the frame. *f*² is its enlarged end, adapted to rest in the recessed portion *a*⁴ of 95 the butt of the pistol. Its other end, *f*³, has resting upon its upper grooved side the end of a spring, *g*, which holds the enlarged end *f*² against the butt-end of the pistol-frame. Its operation is as follows: The end *f*³ is 100 pressed in toward the frame, thus throwing out the end *f*², when a percussion-cap is placed

in the recessed portion a^4 of the butt. The portion f^2 is then allowed to spring down gently upon the cap, holding it in the recess a^1 . The pistol then being grasped by its 5 barrel end is struck upon its butt-end against any hard surface, and the cap is exploded.

I claim—

1. In a toy pistol, the combination, with the 10 spring-pressed plunger b , having a catch, b^3 , of the pivoted lever c , having a catch to engage the same, and a rearwardly-extending spring-pressed arm, and the trigger e , having the extension e^2 , which engages said arm and holds the catch in engagement with the plunger, substantially as shown and described.
- 15 2. In a toy pistol, the combination, with the

spring-pressed plunger b , having catch b^3 , the pivoted catch c , with spring-pressed extension c' , and the hammer d , having the catch d^5 and spring-pressed extension d^3 , of the 20 trigger e , having the catch e^3 , the forward extension, e^2 , and the rear spring-pressed extension or arm, e^4 , all operating substantially as shown and described.

In testimony whereof I have signed my name 25 to this specification in the presence of two subscribing witnesses.

FRANCIS L. GORDON.
